V. GERO

MOUNTING FOR YARN FRAME CLIPS

Filed June 23, 1924

INVENTOR
Victor Gero.
BY *Robert M. Barr*,
ATTORNEY

UNITED STATES PATENT OFFICE.

VICTOR GERO, OF PHILADELPHIA, PENNSYLVANIA.

MOUNTING FOR YARN-FRAME CLIPS.

Application filed June 23, 1924. Serial No. 721,778.

To all whom it may concern:

Be it known that I, Victor Gero, a citizen of the United States, and a resident of Philadelphia, county of Philadelphia, State of Pennsylvania, have invented certain new and useful Improvements in Mountings for Yarn-Frame Clips, of which the following is a specification.

The present invention relates to tuft-yarn frames and more particularly to the clip mechanism by which the respective frames are attached to and released from the frame conveyor chains.

Some of the objects of the present invention are to provide an improved means for mounting spring clips on the ends of a yarn frame; to provide a mounting for spring clips which eliminates screws or other fastening devices of the type which hold the clip by entering the end of the frame and are objectionable because they work loose and back out of the frame to a position where they throw the frame out of alignment and more frequently cause the frame to become disconnected from the conveyer chain; to provide an improved retainer for spring clips which is rigidly held against movement lengthwise of the frame; to provide a holder for spring clips which can be applied to existing clip frame constructions quickly, economically and without any change in the relation of the clip to its associated parts; and to provide other improvements as will hereinafter appear.

In the accompanying drawings, Fig. 1 represents a side elevation of an end of a tuft yarn frame provided with a clip holder embodying one form of the present invention; Fig. 2 represents an end elevation of the same; Fig. 3 represents a section on line 3—3 of Fig. 2; and Fig. 4 represents a perspective of one form of clip holder.

Referring to the drawings, an end of a tuft yarn frame 10 is shown which is of the type formed of a wooden bar 11 encased in a metal tube 12 and of a length to operate with the particular loom for which it is intended. In so far as the present invention is concerned, it seems unnecessary to illustrate both ends of the frame as it will be understood the two constructions are the same.

The end of the frame 10 is provided with rigid uprights 13 and 14, the former serving as the support for the yarn spool and

the latter being offset therefrom to engage a link of the chain by which the frame is carried. Interposed between the uprights 13 and 14 is a spring clip 15 of the usual form which extends from the end of the frame 10 upwardly and outwardly to be held by spring tension against the end of the chain engaging upright 14. A suitable slot 16 is formed in an offset portion 17 of the upright 14 in order to pass the clip 15 to its operative position.

For the purpose of mounting the clip 15 on the end of the frame 10 it is provided with two openings 18 which are located to register with like openings 19 in the base portion of the upright 14 and in alinement with the end of the frame 10. These openings 18 and 19 may be the customary holes to receive the screws by which the clips have heretofore been secured to the upright 14 or to the end of the frame 10. In accordance with the present invention a holder 20 is provided having a flat base 21 arranged to seat on the bottom of the frame 10, and an extension arm 22 arranged at an angle thereto which is preferably slightly greater than a right angle. This arm 22 in operative position extends from the base 21 upwardly over the end of the frame 10 and overlapping that portion of the spring clip 15 which seats on the upright 14. Laterally extending from the arm 22 towards the end of the frame are two lug prongs 23 which are spaced and located to pass respectively through the two sets of openings 18 and 19 where, for purposes of more securely interlocking the parts, they may be embedded in the end of the bar 11.

In order to rigidly hold the arm 22 in its interlocked position clamping the clip to the end of the frame, it is fixed to the bottom of the frame 10 by screws 24 or other suitable fastening means entering the bottom of the frame 10, the holes for such fastening means being so located in the frame 10 as to position the arm 22 in abutting relation to the spring clip 15. It should be noted that the length of the arm 22 is such as to extend beyond the flat seating part of the clip so that its end rests against the angularly disposed part of the clip. This construction provides a clearance space 25 between the said arm 22 and the clip 15 whereby the clip is not flexed along a sharp edge but has sufficient play to distribute the bending stress. Also the clip

15 is backed or reinforced by a separate spring strip 26 which supplements the spring action of the clip 15 and prolongs the life of the clip.

5 It will now be apparent that a complete unitary holding means has been provided for spring clips which is simple in construction, effective in operation and serves to maintain the clip properly supported 10 while providing a smooth contact face positioned towards the conveyor chain.

In clip constructions as heretofore used it has been customary to employ machine or wood screws for fastening the clip to the 15 end of the yarn frame and as a result, when these screws work loose, as they are doing all the time, the added length of the frame due to the projecting screws not only throws the frames out of position but more often 20 causes them to be forced out of the conveyor chain. As these frames weigh many pounds apiece it is a serious thing when one is forced out and drops from the conveyor, the resulting damage requiring many hours 25 lost time in the operation of the loom. Further, the working out of the fastening screws is so common that expert loom repairers are required to be in constant attendance.

30 By the device of the present invention the foregoing defects of prior constructions are entirely eliminated and after a holder of this new type is in place, there is nothing to vary the length of the frame or to obstruct 35 the path of the conveyor chain or its associated parts. Furthermore, by the provision of a plurality of interfitting lugs, the clip is firmly held against movement relative to either the upright or the holder.

40 Attention is also directed to the fact that the frames to which these clips are applied are nine feet or more long and two men are required to handle each frame when it is placed in the loom, so that it will readily 45 be seen that if one of the frames is displaced on account of the usual screw fastening means working loose, that resulting damage is not only apt to be heavy, but when one frame drops out of the chain, it generally 50 carries several others with it and the entire loom is put out of commission.

In connection with the clip holding means of the present invention, it will be noted that the holders which carry the interfitting 55 prongs are interchangeable and can be used at both ends of the frame instead of having

to provide one holder as a right hand holder and the other as a left hand holder.

While only a single form is shown in which this invention may be embodied, it is 60 to be understood that the invention is not limited to any specific construction, but might be applied to various forms without departing from the spirit of the invention or the scope of the appended claims. 65

Having thus described my invention, I claim:

1. In a yarn frame construction, the combination of a yarn frame, a spring clip provided with openings therein aligned with the end of said frame, a holder, an arm on said holder having lugs to pass respectively through said clip openings, and means for securing said holder to said frame to clamp said clip in position. 75

2. In a yarn frame construction, the combination of a yarn frame, a spring clip provided with openings therein aligned with the end of said frame, a holder comprising a base seating against said frame and an arm extending substantially parallel to the end of said frame, lugs on said holder for respectively traversing said openings, and means for fastening said holder base to said frame to clamp said clip in position. 85

3. In a yarn frame construction, the combination of a yarn frame, a spring clip provided with an opening aligned with the end of said frame, a holder, an arm on said holder having a lug to pass through said opening, and means for securing said holder to said frame to clamp said clip in position. 90

4. In a yarn frame construction, the combination of a yarn frame, a spring clip provided with openings aligned with said frame, said clip having a portion seating against the end of said frame and a portion diverging therefrom, a holder, an arm on said holder having lugs respectively passing through said openings, said arm being of a length to engage the diverging portion of said clip, and means for securing said holder to said frame to clamp said clip in position by rigid engagement with one portion of said clip and yielding engagement with another portion of said clip, whereby the bending stress on said clip is distributed. 100

Signed at Philadelphia, county of Philadelphia, State of Pennsylvania, this 11th day of June, 1924. 110

VICTOR GERO.
